UNITED STATES PATENT OFFICE.

EMIL R. ANDERSON, OF CHICAGO, ILLINOIS.

FURNACE GRATE.

Application filed February 7, 1921. Serial No. 443,080.

To all whom it may concern:

Be it known that I, EMIL R. ANDERSON, a subject of the King of Sweden, and resident of the city of Chicago, in the State of Illinois and United States of America, have invented certain new and useful Improvements in Furnace Grates, of which the following is a full, clear, and exact description.

This invention relates to improvements in furnace grates and the object of the invention is to provide a grate which may be very easily operated to clear the same of ashes and clinkers.

A further object is to provide a grate from which the refuse is discharged at the front end of the furnace.

A still further object is to provide a grate which will not be readily burnt out and which will supply preheated air to the fire.

The invention resides in providing a pair of similar side plates each having an endless groove therein. Grate members are slidably mounted between the plates in the grooves thereof and means are provided engaging the grate members to circulate the same in such a manner that the upper or fire bearing grates move from the back of the furnace toward the front, where a pivoted apron is provided to receive refuse and also any good fuel. The apron is provided with a supporting latch which may be tripped to release the apron to dump refuse into the ash pit. The grate bars are hollow and communicate at their ends with air channels in the side plates, through which air may flow from the ash pit into the bars and from the bars into the furnace.

In the drawings which illustrate the invention:—

Fig. 1 is a fragmentary plan view of the device with parts omitted.

Fig. 2 is a vertical longitudinal section of the device.

Fig. 3 is a vertical cross section of the device.

Fig. 4 is a plan view of a single grate unit.

Fig. 5 is a fragmentary plan view illustrating an alternative formation of the grate bars.

Fig. 6 is a fragmentary plan view illustrating a further alternative arrangement of grate bars.

Referring more particularly to the drawings, 11 designates a pair of similar side plates adapted to be supported at opposite sides of a furnace in any suitable manner.

Each plate is provided with an endless track groove 12 having spaced upper and lower portions and curved end portions connecting them. The plates between the upper and lower portions of the grooves are provided with air channels 13, to which air is admitted either through openings 14 from the ash pit or from any other source. Openings 15 are provided at intervals leading from the air channels 13 into the upper parts of the grooves 12 and openings 16 are provided leading from the grooves into the furnace above the grates.

The grate bars 17 are preferably tubes of any suitable cross section arranged in series, as shown in Figure 4, the bars of each series being connected at their ends to hollow spacers 18 having outwardly projecting tubular lugs 19 engageable in the grooves 12 to support the bars. The hollow lugs and hollow spacers permit air flow from the grooves into the bars 17 and from the bars into the furnace. These spacers hold the bars a proper distance apart and thus ensure parallelism of the bars and proper spacing to support the fuel and to give adequate draught. As shown in Figure 2, adjacent grate units are in contact, so that an endless grate structure is formed, the upper portion only of which carries burning fuel while the lower portion is idle. A shaft 20 is journaled in the rear ends of the plates 11 and extends transversely of the furnace. A plurality of sprockets 21 are rigidly mounted on the shaft, the teeth thereof being shaped to engage between the bars 17. An apron 22 may be provided at the rear end of the device close to the upper layer of bars and extending rearwardly thereof to fill the space between the curved end of the row of bars and the back of the furnace, in order to prevent fuel falling at the rear of the furnace.

At the front of the furnace, an apron 23 is pivotally mounted with its rear edge close to the bars and slightly below the level of the top row. This apron is designed to swing between the grate and the front 24 of the furnace and to form a connection 105 between the grates and the furnace doorway corresponding to the usual throat plate. The front or free edge of the apron is provided with a bracket 25, in which is pivotally mounted a hooked dog 26 adapted 110 to engage an opening 27 in the front plate 24 and also adapted to pass inwardly

through the opening. A retrieving chain 28 is connected to the free extremity of the dog and is adapted to pass through the opening 27.

5 In the modification shown in Figure 5, the grate bars 29 are mounted directly in the grooves 12 and are not connected in series. Bars of this form are provided with rings or sleeves 30 thereon forming spacers 10 to hold the bars apart.

It will be noted in Figure 1 that the apertures 16 appear in spaced groups in the side plates, the groups of each plate being opposite the spaces between groups of the 15 other plate. It will also be noted that the apertures 15 are in similarly spaced groups opposite the groups of apertures 16. This arrangement provides for the admission of heated air in equal amounts on both sides 20 of the furnace, but it will be understood that the openings 16 may be disposed all in one side plate and the openings 15 all in the other side plate, so that heated air will enter at one side only. In Figure 6 bars are 25 shown as connected in series by spacers 31 through which the ends of the bars may project to have direct engagement with the side plates. When three or more bars are connected in series, it is evident that the 30 ends of two only should project into engagement with the side plates, since if more project difficulty will be experienced in passing the series of groups through the curved portions of the side plate grooves.

35 The operation of the device is as follows;— A fire is built on the grate in the usual manner and, when it is desired to clean the fire, the shaft and sprockets are revolved in a direction to cause the grate bars to 40 travel toward the front end of the furnace, so that residual material on the bars will be deposited on the apron 23 where the operator can separate good fuel from ashes and clinkers. When the apron is sufficiently 45 loaded with refuse, the retrieving chain 28 is given a slight upward pull to disengage the dog from the furnace front or the dog may be struck up with a shovel or the operator's foot. The apron then falls to the 50 vertical position indicated in dotted lines, Figure 2, discharging the refuse into the ash pit. The apron is replaced in normal position by merely pulling on the retrieving chain. The forwardly moving grate bars 55 in the top row pass down at the front end into the lower row and push the bars in the lower row into engagement with the sprockets, so that bars are replaced in the rear end of the upper row at the same rate that they 60 are removed at the front end, the grate being in effect an endless structure. Any good fuel coming forward on to the apron 23 may be thrown to the back end of the furnace. The grate may be set in motion 65 only when desired or may move slowly and

continuously if the system of firing and the fuel permit the same. A stoker attachment has not been illustrated but if such is used it will be disposed to discharge fresh fuel into the rear end of the furnace. Refuse falling between the bars of the upper row will also pass between the bars in the lower row and into the ash pit, very little refuse, if any, remaining on the lower row of bars. If it is not desired to thoroughly 70 clean the fire, the grates may be shaken by oscillating the sprockets, so that the bars will be moved back and forth rapidly in the furnace and any refuse dislodged. Air flows into the ash pit in the usual manner 75 and is slightly heated by contact with hot refuse therein. Part of this air rises between the grate bars in the usual manner and part flows into the air channels 13 of the side plates and from thence through the 80 hollow bars of the upper row and into the furnace. Preheated air is thus discharged into the furnace and at the same time the bars are cooled and prevented from burning. 85

With a grate according to this invention, 90 the work of cleaning fires and grates is greatly simplified as the fuel and refuse are moved to the front of the furnace instead of to the back, as is customary with chain or endless grates. Less than half the bars 95 of the furnace are in use at one time, so that overheating is prevented and, in addition, the bars carrying fuel are cooled by air flow therethrough so that burning out of bars is entirely eliminated. In the case of separate 100 bars as shown in Figure 5, the bars will revolve to a certain extent about their axes, so that they do not tend to sag as do bars which are always in the same relation to the fuel. 105

Having thus described my invention, what I claim is:

1. In a furnace, a grate comprising a pair of side plates, bars slidably supported therebetween and forming, in effect, an endless 110 grate, said bars being hollow to provide air passages therethrough and air passages formed in the side plates connecting the air passages of the bars with the ash pit and with the fire box of the furnace. 115

2. In a furnace, a grate comprising a pair of side plates, bars slidably supported therebetween and forming, in effect, an endless grate, said bars being hollow to provide air 120 passages therethrough and air passages formed in the side plates connecting the air passages of the bars with the ash pit and with the fire box of the furnace, said air passages being disposed to conduct air to both sides of the furnace.

3. A grate comprising a pair of side plates, provided with air passages, bars slidably supported between said plates and forming, in effect, an endless grate, said bars being hollow to provide air passages 130

- therethrough, hollow spacers rigidly connecting the bars in groups, each of said spacers having a pair of tubular supporting lugs in slidable engagement with the said 5 plates to support the bars and to form air inlets and outlets therefor, said lugs being in communication with the passages of the side plates.
4. In a furnace, a grate comprising a 10 pair of side plates, bars slidably supported therebetween and forming, in effect, an endless grate comprising upper and lower layers, means to circulate said grate in such a direction that the upper layer moves toward the 15 front of the furnace, an apertured furnace front, an apron hingedly mounted at the front end of the grate to receive material from the bars of the upper layer, a bracket on the apron, a hook pivotally mounted on 20 the said bracket and adapted to engage the furnace front through the opening thereof to support the apron in receiving position, a retrieving chain connected to said hook to raise the apron to receiving position and to 25 draw the hook into operative engagement with the furnace front.
5. A grate comprising a pair of side plates, each of said plates being provided with an endless track groove and with an 30 air passage encircled by said track groove and having air inlets, each plate being further provided with spaced passages leading from said first mentioned passage into said track groove and with spaced air passages 35 leading from the track groove and disposed in the spaces between said second passages and a plurality of hollow grate bars extending between said plates and having open ends disposed in said track grooves.
6. In a furnace, a grate comprising an 40 endless series of hollow grate bars and guides therefor, the construction comprising means for effecting a circulation of air through said guides and grate bars from the 45 ash pit to the fire box of the furnace.
7. A grate comprising an endless series of hollow grate bars, guides therefor having endless channels slidably receiving the ends of said bars, said guides being provided with air passages coacting with said channels to effect a circulation of air through 50 said bars from the ash pit of a furnace to that portion of the furnace above the grate.
8. A grate comprising a pair of side 55 plates, hollow grate bars slidably supported therebetween and forming in effect, an endless grate, each of said side plates being provided with an endless groove for said bars, each groove having air inlets in the lower wall of the upper portion thereof and air 60 outlets in the upper portion thereof above the spaces between the inlets and an air passage formed in each plate encircled by the groove and communicating with the air inlets leading to the groove and air inlets leading 65 to said passage.

In witness whereof, I have hereunto set my hand.

EMIL R. ANDERSON.
